Attest

UNITED STATES PATENT OFFICE.

HARRY F. CLARK, OF NEW HAVEN, CONNECTICUT, ASSIGNOR TO CLARK BROTHERS,
A FIRM COMPOSED OF HIMSELF, CLIFFORD R. CLARK AND ROBERT E. CLARK, OF
NEW HAVEN, CONNECTICUT.

SCAFFOLD BRACKET.

Application filed February 26, 1926. Serial No. 90,730.

I do hereby declare the following, when taken in connection with the accompanying drawings and the characters of reference marked thereon, to be a full, clear, and exact description of the same, and which said drawings constitute part of this application, and represent, in—

Fig. 1 a plan view of a scaffold bracket constructed in accordance with my invention.

Fig. 2 a side view of the same.

Fig. 3 a sectional view on the line 3—3 of Fig. 2.

Fig. 4 a sectional view on the line 4—4 of Fig. 2.

Fig. 5 a plan view of the lower end of the brace.

This invention relates to improvement in scaffold brackets, and particularly to brackets to be mounted at the corner of a building, so as to support scaffoldings arranged on either side thereof. Brackets for this purpose have been made, but the object of this invention is to provide a bracket which may be readily and firmly secured in position, and the invention consists in the construction as hereinafter described and particularly recited in the claims.

In carrying out my invention, the bracket-bar is preferably formed from two strips 10 and 11 of angle iron riveted together and forming a flat top 12 for the support of planking. The inner ends of these strips are bent outward at angles of 45°, so as to form two integral ends 13 and 14 at right angles to each other, these ends fitting against a corner 15 of a building, to which they are secured by hooks 16 and 17 engaging with corner-studding 18, the threaded ends of the hooks extending outward through the ends 13 and 14 to receive lock-

ing-nuts 19. Pivoted to the bracket-bar, near its outer end, is an angular brace 20 having its lower end 21 divided to fit the corner 15, and this brace is preferably supported from the bracket-bar by a stay 22, which permits the brace to be folded against the bracket-bar. Preferably, the outer end of the bracket-bar will be formed with an upwardly-extending lip 23, to assist in holding the scaffold boards in place.

I thus provide a scaffold bracket for the corners of buildings which is simple in construction, readily fixed in position, and supported by the corner-studding.

I claim:—

1. A scaffold bracket, comprising a bracket-bar having integral rigid inner ends arranged at right angles, a brace pivotally connected with the bracket-bar and provided at its lower end with ends at right angles to each other, means adapted to be engaged with corner-studdings and extending out through the inner ends of the bracket-bar, to which said means are connected.

2. A scaffold bracket, comprising a bracket-bar formed from two strips of angle iron, the inner ends of which are turned outward at right angles to each other, a brace pivotally connected with the bracket-bar, its lower end divided and turned to form a right angle, means for supporting the brace from the bracket-bar, and means adapted to be engaged with corner-studding and extending outward through the ends of the bracket-bar, to which said means are connected.

In testimony whereof, I have signed this specification.

HARRY F. CLARK.
